ROTATABLE FURNACE

Application filed December 7, 1928. Serial No. 324,417.

This invention relates to furnaces containing silicon carbide heating elements in which the furnace is revolved or oscillated in order to stir up the charge and subject it to quicker and more uniform heating. Our principal object is to provide a rotatable furnace (which may be continuously rotated during active operation or oscillated back and forth, having readily replaceable rigid resistors which may be used at temperatures up to 1400° C. Another related object is to provide cooling means for preventing arcing at the terminals of the rigid resistors, which is a matter of great importance where non-metallic resistors are used, since there is a tendency to arcing at the junctions between metal and non-metal, this tendency increasing as the temperature of the junction increases. Still another object is to show the adaptability of our improved furnace to heat treatments of materials in gases other than air or at pressures other than atmospheric. Rotating furnaces of the electric arc type are known. In such furnaces the heating is developed in a very restricted region namely at the incandescent cores of the carbon arcs. The use of silicon carbide resistor rods renders possible much more uniform heating and greater energy output. While in the case of the electric arc heaters the very high local temperatures make it necessary to have the arc approximately at the center of the furnace, silicon carbide resistor rods may be distributed in groups around the axis of the furnace or may be mounted in the refractory lining itself. Such resistors in an enclosed compartment maintain a substantially uniform temperature over about 80% of their length. The latter method of mounting would be impracticable in the case of the electric arc. When used in the refractory lining the silicon carbide resistor elements are easily protected from oxidation and do not require replacement so often as electric arc carbons. This is important from the point of view of continuity of service.

Our improved rotating furnace is illustrated in the accompanying drawings in which:

50 Figure 1 is an elevation partly in section

of a rotatable furnace provided with stationary resistor elements, the section being taken parallel to the resistor rods;

Figure 1—A is a view similar to that of Fig. 1 of an enclosed furnace in which the heating elements turn with the muffle;

Figure 1—B is a detail indicating a means of water-cooling the metal terminals of the resistor rods shown in Fig. 1;

Figure 2 relates to the same type of furnace as in Fig. 1 and indicates a sectional elevation of the furnace taken at right angles to Fig. 1 on line II—II;

Figure 3 is a vertical section of a rocking or oscillating furnace taken parallel to the resistor rods;

Figure 4 is a section taken at right angles to Fig. 3 taken on the line IV—IV;

Figure 5 is a section of a rotatable cylindrical muffle in which the resistor rods are separated from the muffle by a reduced portion of the lining of the muffle, the section being taken at right angles to the axis of rotation;

Figure 6 is a view of the resistor rods of the last-mentioned furnace shown in position in grooves in the refractory lining with the cover which supports the rods cut away;

Figure 7 is a sectional view of the muffle in the last-mentioned type of furnace taken through the axis of rotation;

Figure 8 is a view similar to Fig. 6 but showing the cover which is just outside the resistor rods and which supports them;

Figure 9 is a detail view indicating a manner of mounting a resistor rod in the type of furnace illustrated in Figures 5—11;

Figure 10 is a modification of the mounting for a resistor rod shown in Fig. 9; and

Figure 11 indicates a method of water-cooling the metal terminals for the resistor rods in the type of furnace shown in Figures 5—11.

In the type of furnace shown in Fig. 1 there are a series of stationary silicon carbide resistor rods 1 surrounded by a muffle 2, which is mounted on rollers 11 for turning around an axis parallel to the resistor rods. The latter are supported in water-cooled terminals (for details of cooling see Fig. 1—B) 100

4, at either end of the furnace. At the left end as shown in Fig. 1 the terminals 4 are supported on the rigid members 5. At the right hand end the water-cooled terminals 4 are subjected to adjustable spring pressure 5 and are connected to and supported on spring-pressed rods which can slide through the rigid support 7. The springs 8 take care of the change of length of the silicon carbide rods 1 due to changes of temperature.

10 The muffle in the type shown in Fig. 1 has a refractory lining 9 contained in an iron shell 10. The latter carries annular projections or tracks by means of which the furnace 15 may turn on rollers 11. These supports 5 and 7 may be mounted on a frame so that the axis of the furnace A may be horizontal or inclined at any angle. In Fig. 1 pivots *a* and *b* are indicated about which the furnace may 20 be turned on axes that are perpendicular to the plane of Fig. 1.

The metal terminals indicated generally in Fig. 1 by the numeral 4 are shown in Fig. 1—B as made up of two portions with provision for water-cooling. The metal terminal 25 29 may be made of a high heat resisting alloy, for example of chrome iron containing about 27 percent chromium. The part 30 may be of iron welded on to 29. Water circulation is indicated as taking place through 30, which has rubber hose connections at inlet and outlet. Electrical connections may be made at 31 or any convenient portion of the metal terminal.

35 A plug is shown as at 33 in Fig. 2 to indicate in a conventional manner removable means for closing an opening through which the charge may be inserted or abstracted.

Figure 1—A indicates a type of rotatable furnace which may be completely enclosed, the current being led in by means of stationary brushes, which contact with the rings 32 which rotate with the furnace. The muffle along with the resistor rods and spring-pressed metal terminals are rotatable as a body with respect to the stationary brushes 27. Gas ports 42 and 43 respectively, may be provided for giving a non-oxidizing or other form of atmosphere in the muffle as required. 45 A certain amount of water-cooling may be effected by directing jets of water on the metal disks 5'.

In Figures 3 and 4 there is shown a type of furnace adapted for an oscillating movement as contrasted with the type shown in Figures 1, 1—A and 2, which are adapted for continuous rotation in one or the other direction. A removable plug 34 is shown for closing the outlet for the finished product. A somewhat larger charging opening is provided which may be closed by the plug 35. The resistor bars are mounted in a removable cover 13. Metal terminals 4' are indicated. These may be water-cooled as indicated in Fig. 1—B.

The type of furnace indicated in Figures 5—11 is intended for continuous rotation. The resistors are indicated in Figures 5, 6 and 7 as partly enclosed by refractory 15, grooves being provided in the latter for this purpose. 70 Heat developed in the resistors is thus conducted through comparatively thin portions of the refractory to the interior of the muffle. The resistor bars are supported on a removable cover 16 which is indicated in Fig. 75 8 as lying between the rings 21 for electrical connections. Tracks 17 are provided for the rotation of the muffle. In Fig. 9 the resistor rods 1 are shown as mounted between chrome steel springs. The latter are fastened to insulating blocks 36 by means of bolts 38 which are also connected to flexible leads 39 for making electrical connection with the rings 21. The rings 21 are mounted on other insulating members 37. The latter may be bonded by means of refractory cement to the refractory lining of the muffle or otherwise fastened thereto. The cover 16 may be bound to the refractory by locking means not shown during the operating of the furnace. When 90 unlocked the cover may be removed on disconnecting the electric leads.

In the modification shown in Fig. 10 the rigid bars 22 take the place of the springs 19. The spring 40 takes care of changes of length 95 of the resistor rod due to changes of temperature. The terminal 24 has a sliding contact with bar 22.

In Fig. 11 means are shown by which metal terminals for non-metallic resistor elements 100 may be water-cooled. The spring pressed metal terminals 41 are in thermal contact with troughs 26 which extend completely around the muffle, but these terminals should preferably be thermally insulated from the 105 heat conducting inner lining 15 of the furnace. Water is dropped from pipes 25 through perforations 51 and is received after it has abstracted a certain amount of heat from the metal terminals in outlets 52. 110

Nichrome or similar metallic resistors are not suitable for use in heating furnaces above 1100° C. Resistor rods of the type illustrated in our drawings but made of graphite or bonded carbon may also be used at such 115 low temperatures, where their tendency to oxidation is not too severe, but for use at temperatures above 1100° C. we may use silicon carbide resistors. The latter can be used at temperatures up to 1400° C. and when protected from oxidation can be used at temperatures up to 1600° C. 120

From the foregoing description it will be seen that silicon carbide resistor rods may be used in a variety of rotating furnaces. 125 As compared with arc furnaces of this type they have the advantage of greater uniformity of heating and of longer life. Means for protecting the ends of the rods from arcing have been indicated in the drawing and in 130

the foregoing specification. The tendency to arcing is reduced by using metal terminals which have low vapor pressures at the temperatures used. The temperatures at the contacts between metal and non-metal are in general kept down by water-cooling. The main parts or bodies of the resistor rods may be protected from oxidation by painting the rods with a non-reactive glaze such as is described in copending application No. 228,492, filed Oct. 24, 1927. With these various precautions the life of the resistor rods will be much greater than that of the rods used in rotating arc furnaces.

15 As compared with metals silicon carbide has several advantages. On account of its higher resistivity (which is also higher than that of carbon) it can be used in rods of large cross-sectional area and shorter length than 20 is possible in the case of metals and carbon resistors. Silicon carbide can be used up to temperatures of about 2000° C. It decomposes at 2200° C. It can be used therefore at temperatures much higher than metal resistors in commercial use. Silicon carbide has also a very high emissivity and a low coefficient of expansion. The furnace described in this specification may be used with a high input of energy because of the fact that silicon carbide does not melt below about 2200° C., at which temperature it decomposes, and also because it has a high emissivity and a high thermal conductivity.

25 Silicon carbide resistor rods have been used for five hundred hours in an enclosed muffle. The length of time that they can be used depends on the temperature at which they are run, and on the means taken for protecting them from oxidation. With suitable precautions they may be used more than 40 100 hours at temperatures above 1100° C.

We claim:

1. In a rotatable furnace, non-metallic heating elements of a rigid self-supporting character mounted to rotate with a heating chamber and supported on a removable portion thereof, said heating elements being freely accessible for replacement when said portion of the heating chamber is removed.
2. In a rotatable electric furnace, non-metallic resistor elements mounted for rotation with said furnace, each of said elements being in butt-end engagement with a resilient metallic connecting terminal, water-cooled metallic terminals for the same, and a removable portion of the furnace to which said resistor elements are ordinarily attached, the elements being freely accessible for replacement when said portion of the furnace is removed.
3. In an electric furnace an enclosed heating chamber mounted for rotation, and a plurality of rigid non-metallic resistors capable of withstanding temperatures greater than 65 1,100° C., each of said resistors having a butt-

end engagement with a metallic connecting terminal supported by said heating chamber, and said heating chamber having an inner surface which is curved in planes perpendicular to its axis of rotation whereby rotary displacements of the heating chamber change the position of the charge within the chamber with respect to the resistors.

4. A rotatable electric furnace having a compartment for material to be heated, a heat conducting lining adjacent said compartment and rigid non-metallic heating resistors mounted on a removable portion of said furnace in such a manner as to be freely accessible for replacement when said portion of the furnace is removed, said resistors being separated from the said compartment by the heat conducting lining.

5. In an electrical furnace, a refractory casing, non-metallic resistors within said casing for heating said furnace, each of said resistors being mounted for rotation with the furnace by butt-end engagement with at least one resilient metallic connecting terminal and a cover removable from said casing to which cover said resistors are removably attached.

6. In a rotatable furnace, a refractory casing, non-metallic resistors for heating said furnace, and a cover removable from said casing in which said resistors are mounted in such a manner as to be freely accessible for replacement when said cover is removed from the furnace.

7. In a rotatable electric furnace, a refractory casing, resistors consisting mainly of silicon carbide for heating said furnace, and a cover removable from said casing in which cover said resistors are mounted in such a manner as to be freely accessible for replacement when said cover is removed.

8. In an electrical furnace, a substantially air tight casing, non-metallic resistors for heating said furnace, and a cover removable from said casing, each of said resistors being mounted in butt-end engagement with short resilient metallic connectors attached to said cover.
